FOLDING MACHINE

Santo Azzara, New York, N. Y., assignor of fifty per cent to Andrew Geller Shoe Manufacturing Co. Inc., Brooklyn, N. Y., a corporation of New York

Application September 7, 1944, Serial No. 552,972

12 Claims. (Cl. 12—17)

This invention relates to an improved machine for folding edges of blanks over the body of the blank, and pressing such edges into firm engagement with such body, the edges usually being provided with an adhesive to firmly and permanently secure such edges to the body.

In certain types of shoes, it has been customary to apply a decorative binding to the edge of an insole, upper, or other portion of the shoe to conceal such edge. In many instances, these bindings have been secured by stitching or otherwise. It has been found more desirable, however, to secure the edge bindings by the use of an adhesive, which method of application requires less time than the stitching operation. It is open to the objection, however, that wrinkles are often produced, due in part to an insufficient wiping action to smooth the edges of the binding over the marginal edges of the work, and in part to a deficient application of pressure to the edges after they have been wiped into position.

It is an object of the present invention to provide means for effecting a smooth wiping action over all parts of the edge of the margin, while the work is held immovable, which wiping action is immediately followed by the movement of a hammer element which presses the edges of the binding into firm engagement with the work. The edges of the work are usually curved, and a plurality of wiping elements, each moving generally perpendicular to a line tangent to a section of the curve, are actuated by a single operating mechanism. The wiping action is such as to cause the binding to cling closely to the edge of the work.

In addition to providing an improved edge-binding machine capable of producing work of high quality, wherein the binding is drawn tightly around the edge, the machine of the present invention may also be used for folding the edges of the work over the body of the work to form a hem. In some instances, especially in the case of shoe uppers, it has been a practice, in order to form a neat joint between separate parts, to skive the edges of the leather blanks and fold such edges so that the grain side of the leather extends completely around the margin. A machine constructed in accordance with the present invention accomplishes this result in an effective manner, the edges, skived or otherwise, being tightly drawn over the body of the blank and pressed into adhesive engagement with such body.

The machine of the present invention is far less complicated, and is more easily operated, than other machines which accomplish inferior re-

sults. It may also be readily changed to operate on differently shaped pieces.

Other objects and advantages of the present invention will be hereinafter pointed out, or will become apparent as the specification proceeds.

In the drawings:

Fig. 1 is a side elevation of the head of the press equipped with the folding means of the present invention.

10 Fig. 2 is a broken top plan view of the bed of the press, the view showing particularly the operation and construction of the reciprocating blades which perform the folding operation, and also showing such blades in advanced position.

15 Fig. 3 is similar to Fig. 2, but shows the blades in fully retracted position.

Fig. 4 is a broken vertical section taken on line 4—4 of Fig. 3.

20 Fig. 5 is similar to Fig. 4, but shows the position of the marginal edge of the blank after it has been wiped inwardly by the blades.

Fig. 6 is also similar to Fig. 4, but shows the position of the parts when the marginal edge is engaged by the hammer.

25 Fig. 7 is a bottom plan view of the combined hammer and presser foot.

Fig. 8 is a section taken on line 8—8 of Fig. 4.

Fig. 9 is a broken section taken on line 9—9 of Fig. 8.

30 Fig. 10 is a plan view of a blank which may be secured to a shoe part employing the machine of the present invention.

Fig. 11 is a broken plan view of the shoe part after the blank of Fig. 10 has been secured in place.

The folding and pressing arrangement of the present invention may be employed in connection with any suitable press having a head 10 carried by an arched member 11 which may be formed integrally with frame 12. A chuck 13 may be mounted for reciprocating, vertical movement in the head 10, and suitable means (not shown) may run from the head through the arched support 11 to the base, such means being preferably connected with a foot pedal (not shown) for reciprocating the chuck 13. The chuck is formed with a bore (not shown) which receives a shank 14, which supports the combined hammer and presser-foot structure, the shank being secured within the chuck by means of a set screw 15. The hammer element 17 may be formed integrally with the shank 14, such construction being illustrated in Fig. 4. The hammer portion 18 on the lower surface of the hammer element may have a contour of any desired

shape, depending upon the contour of the work which is being operated upon. In the embodiment illustrated, the work 20, shown in Fig. 11, is an insole for a shoe, and a toe piece 22 having a pinked edge 23 of generally convex curvature is to be secured to such insole, the pinked edge, as well as the remaining terminal edge portions 24, being folded around the curved, forward, terminal portion of the insole 20. In this instance, the outer edge 25 of the hammer may follow the contour of insole 20.

The lower surface of the hammer element 17 is formed with a recess 26 of sufficient depth to receive a plate 27 forming the presser foot which holds blank 20 in position during the folding operation. The body of hammer element 17 is formed with a plurality of apertures 31 which receive pins 32, which may be secured, as by welding 33, in suitably-spaced apertures in plate 27. Referring to Fig. 8, it will be seen that three of such pins 32 are provided for mounting plate 27, thus assuring the plate of easy reciprocating movement without any danger of binding. Downward movement of the plate 27 relative to the hammer element 17 is limited by means of bolts 34 whose heads engage the upper surface of hammer element 17. The plate 27 is normally urged downwardly by means of a relatively large spring 35 positioned within centrally-disposed recess 36 in the hammer element, and a plurality of somewhat smaller springs 40 are positioned within recesses 41, the general location of such smaller springs and recesses likewise being illustrated in Fig. 8.

The press may have a bed 42 mounted on frame 12, such bed having a work support 43 extending therefrom in the direction of the operator. Bed 42 is formed with a recess 48 shaped substantially similar to the contour of the outer marginal edge 25 of the hammer portion 18. The lower surface 44 of this recess is desirably on the same plane as that of work support 43. The toe piece 22, which is provided with the usual adhesive on one surface thereof, is first applied to the insole 20, in which position its pinked edges 23 and relatively-straight edges 24 occupy the position shown in broken lines in Fig. 11. The insole is next inserted within recess 48 in bed 42, the outer marginal edges of the insole being shaped generally similar to the edge of the recess 48, as previously pointed out. In this position, the outer marginal edges 23 of toe piece 22 will be positioned perpendicular to the bed, all as shown in Fig. 4.

The first step in the operation is to depress plunger 13 carrying hammer element 17 to a point wherein presser plate 27 engages insole 20, as shown in Fig. 4. The operator will readily determine the amount of pressure to be applied to the foot pedal to cause the plate to firmly engage the insole, without, however, moving the hammer element downwardly sufficiently far to interfere with the operation of the wiper blades, which will now be described. For the purposes illustrated, three of such wiper blades 45, 46 and 47 are employed. Central wiper blade 46 is mounted in a recess (not shown) in the upper surface of bed 42, and is adapted to move longitudinally with respect to the frame. Blades 45 and 47, respectively, are mounted in similar recesses for reciprocating movement, and are movable generally diagonally relative to blade 46. Blades 45 and 47 are formed with projections 50 and 51, which, when the blades are in the retracted position shown in Fig. 3, overlie similar projections 52 and 53 disposed on opposite sides of blade 46.

The following means are provided for manually moving the three wiper blades conjointly. A lever 54 is journalled at 55 on the upper surface of the bed, such lever having an elongated slot 57 which engages a pin 61 carried on a plate 62 which is slideable on the upper surface of the bed. Slots 63 and 64 disposed on opposite sides of plate 62 receive screws 65 which pass into the bed, and thus define the path of reciprocating movement of plate 62. Stop pins 66 may also limit forward movement of plate 62. Central wiper blade 46 is keyed to movement with plate 62 by means of pin 70. Also, pins 71 and 72, respectively, carried by plate 62 are received in slots 73 and 74 in diagonal wiper blades 45 and 47. It will thus be seen that when the outer terminal of the handle is moved forwardly, plate 62 likewise moves forwardly and brings the wiper blades to the position shown in Fig. 2.

The lower edges of wiper blades 45, 46 and 47 are so positioned relative to the lower surface 44 of recess 48, which receives the work 20, as to smoothly and tightly wipe the edges 23 and 24 of the toe piece over the marginal edge of the work 20, and when the machine is properly operated, the hammer element 18 may descend upon the edge instantly upon the blades being retracted, thus not permitting a sufficient lapse of time between the operations to enable the slightly-pressed marginal edges to be freed from their adhesive engagement with the work. It was earlier pointed out that the machine of the present invention may likewise be used in cases wherein the work itself has edges which are folded and pressed into engagement with the body of the work, as distinguished from the separate blank illustrated in the drawings. It will be noted that the several wiper blades move in a direction generally perpendicular to lines drawn tangent to the curved edges of the work 20, and in the event that a differently-shaped piece of work is to be operated upon, a separate set of blades may be appropriately employed. In this case, an appropriately-shaped hammer element will also be employed.

While one form or embodiment of the invention has been shown and described for illustrative purposes, and the construction and arrangement incidental to a specific application thereof have been disclosed and discussed in detail, it is to be understood that the invention is limited neither to the mere details of relative arrangement of parts, nor to its specific embodiment shown herein, but that extensive deviations from the illustrated form or embodiment of the invention may be made without departing from the principles thereof.

What I claim is:

1. In a machine for folding and pressing edge material, the combination of a work support having a recess whose edge is shaped to fit the marginal edge of the work and to deflect the edge to be folded upwardly when the work is inserted within the recess, folding means for wiping the edge inwardly, a hammer element for pressing the edge to be folded into firm engagement with the body of the work, and a spring-urged presser plate associated with the hammer element for holding the work immovable during the wiping operation, said wiping means comprising a plurality of wiper blades mounted for reciprocating movement, means for moving the blades conjointly to folding position, and means for moving the hammer element downwardly into edge-pressing position.

2. In a machine for folding and pressing edge bindings, the combination of a work support having a recess whose edge is shaped to fit the marginal edge of the work and to deflect the free edge of the binding upwardly when the work is inserted within the recess, folding means for wiping the edge of the binding inwardly, a downwardly-movable hammer element for pressing the edge of the binding into firm engagement with the work, and a presser plate associated with the hammer element for holding the work immovable during the wiping operation, said wiping means comprising a plurality of wiper blades mounted for reciprocating movement, means for moving the blades inwardly, the hammer element having a recess in its lower wall for receiving the presser plate when the hammer is moved downwardly to edge-pressing position, and spring means for urging the presser plate downwardly into work-holding position.

3. In a machine for folding and pressing the edge of a piece of work onto the body of the work, the combination of a work support having a recess whose edge is shaped to fit the marginal edge of the body of the work and to deflect the edge to be folded upwardly when the work is inserted within the recess, folding means for wiping the edge of the work inwardly, a hammer element for pressing the folded edge into firm engagement with the work, and a spring-urged presser plate associated with the hammer element for holding the work immovable during the wiping operation, said wiping means comprising a plurality of wiper blades mounted for reciprocating movement, a single operating member for moving the blades inwardly, and a vertically-movable support for the hammer element permitting movement of such hammer element downwardly into edge-pressing position.

4. In a machine for folding and pressing edge bindings, a work support having a recess whose edge is shaped to fit the marginal edge of the work and to deflect the free edge of the binding upwardly when the work is inserted within the recess, folding means for wiping the edge of the binding inwardly, a hammer element for pressing the edge of the binding into firm engagement with the work, and a presser plate associated with the hammer element for holding the work immovable during the wiping operation, said wiping means comprising a plurality of wiper blades mounted for reciprocating movement, a single operating member for moving the blades inwardly, the hammer element having a recess in its lower wall for receiving the presser plate when the hammer is in edge-pressing position, spring means for urging the presser plate downwardly into work-holding position, and a vertically-movable support for the hammer element for moving such hammer element downwardly into edge-pressing position, and for raising such hammer element and the presser plate out of engagement with the work.

5. In a machine for folding and pressing edge bindings, the combination of a frame, a work support carried by the frame and having a recess whose edge is shaped to fit the marginal edge of the work and to deflect the free edge of the binding upwardly when the work is inserted within the recess, folding means for wiping the edge of the binding inwardly, a hammer element for pressing the edge of the binding into firm engagement with the work, and a presser plate associated with the hammer element for holding the work immovable during the wiping operation,

said wiping means comprising a plurality of wiper blades mounted for reciprocating movement, a single operating member for moving the blades inwardly, the hammer element having a recess in its lower wall for receiving the presser plate when the hammer is in edge-pressing position, spring means for urging the presser plate downwardly into work-holding position, a support for the hammer element, journal means carried by the frame to permit vertical, reciprocating movement of the hammer element, means for moving such hammer element downwardly to cause the presser plate to engage the work while the lower surface of the hammer element is spaced from the work, thus permitting wiping movement of the blades, and means for moving such hammer element into edge-pressing position after the blades have been retracted.

6. In a machine for folding and pressing edge portions of a piece of work into engagement with the body of the work, the combination of a work support having means for receiving the marginal edges of the body of the work, means for wiping such edge portions inwardly, means for holding the work against the work support during the wiping operation, and a vertically-movable hammer element for pressing the folded edge portions firmly into engagement with the body of the work, the wiping means comprising a plurality of wiping blades movable generally at right angles to the edge sections comprising the marginal edges of the body of the work, and means for moving the blades into wiping position.

7. In a machine for folding and pressing edge portions of a piece of work having a curved contour into engagement with the body of the work, the combination of a work support having means for receiving the marginal edges of the body of the work and deflecting the edge portions upwardly, means for wiping such edge portions inwardly, spring-urged means for holding the work against the work support during the wiping operation, and a vertically-movable hammer element for pressing the folded edge portions firmly into engagement with the body of the work, such hammer element carrying the work-holding means, the wiping means comprising a plurality of wiping blades movable generally at right angles to lines tangent to the curved edge sections comprising the marginal edges of the body of the work, and means for moving the blades conjointly.

8. In a machine for folding and pressing edge portions of a piece of work into engagement with the body of the work, such edge portions being provided with an adhesive, the combination of a work support, means for wiping the edge portions of the work inwardly, means for holding the work against the work support during the wiping operation, and a vertically-movable hammer element for pressing the folded edge portions firmly into engagement with the body of the work, the wiping means comprising a plurality of wiping blades movable generally at right angles to the edge sections comprising the marginal edges of the body of the work, and a lever connected with such blades for moving the blades conjointly to folding position, the work-holding means comprising a spring-pressed plate mounted on the lower surface of the hammer element for vertical, reciprocating movement.

9. In a machine for folding and pressing edge portions of a piece of work into engagement with the body of the work, the combination of a frame, a work support carried thereby and having means

for receiving the marginal edges of the body of the work and deflecting the edge portions upwardly, means for wiping such edge portions inwardly, means for holding the work against the work support during the wiping operation, and a vertically-movable hammer element for pressing the folded edge portions firmly into engagement with the body of the work, the wiping means comprising a plurality of wiping blades movable generally at right angles to the edge sections comprising the marginal edges of the body of the work, means for moving the blades conjointly, the work-holding means comprising a spring-compressed plate mounted on the lower surface of the hammer element for vertical, reciprocating movement, such lower surface having a recess to receive the plate when the hammer is in pressing position, journal means carried by the frame for permitting vertical, reciprocating movement of the hammer element, means for moving the hammer element downwardly to cause the plate to engage the work during the wiping operation, and means for moving the hammer element into engagement with the work upon retraction of the wiping blades.

10. In a machine for folding and pressing edge portions of a piece of work into engagement with the body of the work, the combination of a work support having means for receiving the marginal edges of the body of the work and deflecting the edge portions upwardly, means for wiping such edge portions inwardly, means for holding the work against the work support during the wiping operation, and a vertically-movable hammer element for pressing the folded edge portions firmly into engagement with the body of the work, the wiping means comprising a plurality of wiping blades movable generally at right angles to the edge sections comprising the marginal edges of the body of the work, and means for moving the blades conjointly, the work-holding means comprising a spring-compressed plate mounted on the lower surface of the hammer element for vertical, reciprocating movement, such lower surface having a recess to receive the plate when the hammer is in pressing position.

11. In a machine for folding and pressing an edge binding to a piece of work formed with a curved edge, the combination of a work support having a recess whose marginal edge is shaped to receive the marginal edge of the work and deflect the edge binding upwardly when the work is inserted within the recess, a hammer element mounted for vertical, reciprocating movement relative to the work support to permit the edge binding to be pressed into firm engagement with the work, a work-holding plate mounted for vertical, reciprocating movement on the lower surface of the hammer element, the lower surface of such element having a recess to receive the plate when the hammer is in pressing position, spring means for urging the plate downwardly into work-holding position, a plurality of wiper blades mounted on the work support for folding the upwardly-deflected edges of the binding inwardly, such blades moving in lines generally at right angles to a line tangent to the several sections of the curved edge of the work, and single operating means for moving the blades into folding relationship.
12. In a machine for folding and pressing an edge binding to the upper surface of a piece of work formed with a convexly-curved edge, the combination of a work support having a recess whose marginal edge is shaped to receive the marginal edge of the work and deflect the edge binding upwardly when the work is inserted within the recess, a hammer element mounted for vertical, reciprocating movement relative to the work support to permit the edge binding to be pressed into firm engagement with the work, a yieldable, spring-urged, work-holding plate mounted for vertical, reciprocating movement on the lower surface of the hammer element, a plurality of wiper blades mounted on the work support for folding the upwardly-deflected edges of the binding inwardly, such blades moving in lines generally at right angles to a line tangent to the several sections of the curved edge of the work, and single operating means for moving the blades into folding relationship.

SANTO AZZARA.
